UNITED STATES PATENT OFFICE.

SAMUEL UPTON, OF ARLINGTON HEIGHTS, MASSACHUSETTS, ASSIGNOR TO SIMON P. MACASKILL, OF CAMBRIDGE, MASSACHUSETTS.

VALVE FOR INTERNAL-COMBUSTION ENGINES.

1,101,590.

Specification of Letters Patent. Patented June 30, 1914.

Application filed September 15, 1913. Serial No. 789,788.

To all whom it may concern:

Be it known that I, SAMUEL UPTON, a citizen of the United States, and a resident of Arlington Heights, county of Middlesex, 5 and Commonwealth of Massachusetts, have invented certain new and useful Improvements in Valves for Internal-Combustion Engines, of which the following is a full and exact description.

10 One of the great dangers found to exist in connection with certain types of puppet valves employed in explosion engines is that of a back-fire's resulting in the ignition of other disturbance of the carbureter's contents; and the object of this invention is the construction of improvements in details calculated to remove all possibility of such accidents.

15 Referring to the drawings forming part 20 of this specification, Figure 1 is a central longitudinal section of a puppet valve embodying my improvements. Fig. 2 is a substantially similar section showing the puppet valve half open.

25 The reference numeral 1 designates part 30 of the cylinder of an internal combustion engine, and 2 the valve casing screwed into the head of said cylinder. The puppet valve 3 which engages the seat 4 in closing the valve opening during the explosions in the cylinder, is carried by the stem 5 controlled in its reciprocation by the helical spring 6 and the rocker arm 7 in the usual manner. Slidable on said stem is a barrel 35 valve 9 whose lower end is formed with an outwardly projecting flange 10 coacting with the seat 11 and adapted to rest upon the latter at the same time that the upper end of the barrel valve wholly encloses the intake 40 openings 12. The lower end of said barrel is closed by a clapper valve 13 slidable on the stem 5 and pressed upward by the puppet valve 3; a helical spring 14 serving to press said barrel downward.

45 Fig. 1 shows the puppet valve 3 approximately half open and just far enough to permit the barrel valve 9 to descend to its seat 11 and widely open the intake openings 12; while Fig. 2 shows said valve opened 50 only about half as far as this. As soon as said valves begin to descend and the puppet valve 3 uncovers the port or seat 4, the exhaust gases from the cylinder rush therefrom out through said port and through the 55 exhaust conduit 15, until, by the time the

barrel valve 9 has reached its seat 11 and cut off further such escape, practically no more exhaust remains in the cylinder. Then, as the puppet valve descends farther, the clapper valve 13 goes with it and opens the lower 60 end of the barrel valve 9. This permits the passage of the charge to the cylinder until the moment the up-stroke of the puppet valve brings the clapper valve 13 into engagement with its seat at the lower end of 65 the barrel valve 9. The puppet valve now quickly returns to its seat 4, and the compression stroke of the cylinder piston begins.

It sometimes happens upon the return 70 stroke of the puppet valve, and when the same has reached substantially the position shown in Fig. 1, that a premature explosion occurs in the cylinder, caused by the latter's getting overheated, and in other ways. 75 When this occurs, the pressure of the exploding gases comes against both the barrel valve and against the clapper, and forces both up together, thereby opening the way to the exhaust conduit. This is permitted 80 by the sliding action of the clapper valve on the valve stem 5.

In previous devices of the kind, what corresponds to the clapper valve 13 is rigid with the valve stem. Consequently, when 85 such backfire occurs, the barrel rises away from the clapper valve and so opens an unobstructed passage to the carbureter. The hot exhaust thus admitted to the carbureter instantly ignites the latter's contents, and a 90 destructive explosion is the result. In my construction, on the other hand, the exposed surface of the clapper valve being greater than that of the barrel valve, and then being nothing to interfere with the former's 95 rising with the latter, it is absolutely impossible for the barrel valve to escape from the clapper valve and so give a dangerous passageway to the carbureter.

The purpose in providing the lower edge 100 of the barrel valve 9 with an outwardly projecting flange 10, is to provide ample seating surface 11, while at the same time allowing sufficient space between the periphery of the clapper valve and the interior of the passage 105 16 for the intake of the charge. Of course, an equal seat can be obtained by making the walls of the barrel quite thick, or by giving the barrel an interior flange. The former construction is objectionable because of its 110

considerably increased weight and its consequent increased wear and tear on the operating machinery and upon its seat 11; while the latter construction is objectionable because of the increased retardation thereby given to the intake of the charge.

At first thought it seemed impossible to assemble a valve wherein the barrel had an outwardly projecting flange at its inner end, 10 since the upper part of the barrel must snugly but slidably fit the cylindrical surface having the ports 12. By making said cylindrical surface in a sleeve 17 integral with the cap 19, I eventually found this 15 could be done, said sleeve being constructed to enter air-tight the opening provided for it in the valve body or casing. In addition to the possible premature ignition of the charge in the cylinder, is the more common 20 danger of an after-fire in the exhaust. While this may not cause an explosion in the carbureter, it disturbs and injures the mixture in the manifold, or intake chamber, and produces a misfire in one or more of the 25 cylinders of a multicylinder engine. Another advantage resulting from having the clapper valve, or intake valve 13, loose upon the valve stem 5, instead of rigid thereon, as in some constructions, is the better engagement 30 with its seat thereby permitted.

What I claim is:

1. A valve for internal combustion engines comprising a valve casing having a seat, a puppet valve coacting therewith having a stem and means for reciprocating said 35 stem, a barrel valve slidably supported by said stem and resiliently pressed toward the puppet valve, a member having a cylindrical

surface slidably surrounding the barrel valve and having an intake port above the 40 upper part of the barrel valve, a seat coacting with the lower end of the barrel valve and communicating with the exhaust conduit, and a clapper valve coacting with the lower end of the barrel valve and slidably 45 carried by said stem, said clapper valve being free to slide upward on said stem when the pressure thereon given by the barrel valve is removed.

2. A valve for internal combustion engines comprising a valve casing having a seat, a puppet valve coacting therewith having a stem and means for reciprocating the same, a barrel valve slidably supported on said stem and resiliently pressed toward the 50 puppet valve, said barrel valve having an outwardly projecting flange at its lower end, a screw cap for said casing having a sleeve 55 tightly fitting the interior of said casing and having its inner surface slidably contacting with the exterior of the barrel valve, said sleeve having one or more ports for the admission of the charge, said casing having a seat communicating with the exhaust conduit and coacting with said flange, and a 60 clapper valve slidable on said valve and coacting with the lower end of the barrel valve. 65

In testimony that I claim the foregoing invention, I have hereunto set my hand this 70 10th day of September, 1913.

SAMUEL UPTON.

Witnesses:

A. B. UPHAM,
HARRY SILVERMAN.

It is hereby certified that Letters Patent No. 1,101,590, granted June 30, 1914, upon the application of Samuel Upton, of Arlington Heights, Massachusetts, for an improvement in "Valves for Internal-Combustion Engines," were erroneously issued to Simon P. MacAskill as assignee of the entire invention, whereas said Letters Patent should have been issued to *the inventor, said Upton and Simon P. MacAskill, jointly*, said MacAskill being assignee of *one-half* interest, only, in said invention as shown by the records of assignments in this office; and that the said Letters Patent should be read with this correction therein that the same may conform to the record of the case in the Patent Office.

Signed and sealed this 21st day of July, A.D. 1914.

[SEAL.]

R. F. WHITING,

Acting Commissioner of Patents.
